HOLDER FOR TOILET PAPER

Denzil D. Snively, San Francisco, Calif.

Application September 27, 1954, Serial No. 32,452

Term of patent 3½ years

(Cl. D4—3)

Fig. 1 is a perspective view of a holder for toilet paper showing my new design.

Fig. 2 is a top plan view;

Fig. 3 is a side elevational view, and

Fig. 4 is a front elevational view thereof.

I claim:

The ornamental design for a holder for toilet paper, as shown.
